W. HACKETT

WATER WHEEL

Filed July 26, 1922

FIG. 1.

FIG. 2.

FIG. 3.

FIG. 4.

FIG. 5.

INVENTOR
WILLIAM HACKETT

BY Fetherstonhaugh & Co

ATTORNEYS

UNITED STATES PATENT OFFICE.

WILLIAM HACKETT, OF PORT ALBERNI, BRITISH COLUMBIA, CANADA.

WATER WHEEL.

Application filed July 26, 1922. Serial No. 577,683.

To all whom it may concern:

Be it known that I, WILLIAM HACKETT, of the town of Port Alberni, in the Province of British Columbia, Canada, have invented 55
5 certain new and useful Improvements in Water Wheels, of which the following is a specification.

My invention relates to improvements in water wheels and the object of the invention 10 is to devise a wheel of this type which will produce a maximum amount of power from the water utilized, to so construct the device to prevent the water roping effect around the periphery of the wheels and to so construct the device that it will not be liable to injury due to stones and other foreign substances being carried thereinto by the water flow and it consists essentially of an enclosed casing having port openings in the 15 opposing walls and an inlet opening in one of the remaining walls, a shaft extending through the walls of the casing having the port openings, a tubular cover for the shaft, right and left hand water wheels mounted 20 upon the shaft at each side of the casing and means for controlling the discharge of water through the port openings against the blades of the water wheels as herein-after more particularly described.

30. Fig. 1 is a perspective view of my device, the tail race cover being removed, its position being indicated by dotted lines.

Fig. 2 is a side view of one of the water wheels employed in my device.

35. Fig. 3 is an edgewise elevation of the water wheel illustrated in Fig. 2.

Fig. 4 is a face view of one port controlling ring and coacting parts.

40. Fig. 5 is a sectional view through the parts shown in Fig. 4.

In the drawings like characters of reference indicate corresponding parts in each figure.

1 indicates a main casing, 2 being the top 45 wall, 3 the side wall provided with port apertures 9, 4 the imperforated front wall and 5 the back wall. 6 is the bottom wall. 7 are orifices formed in the side walls 3 in the centre thereof (see Figs. 4 and 5). 8 is 50 an annular member angular in cross section located at the inside of each side wall around the opening 7. The apertures or port openings 9 are arranged concentrically

around the orifices 7 to the outside of the annular members 8. These port openings 55 are preferably rectangular in form and disposed radially to the centre of the orifices 7. 10 is the feed water supply pipe which extends through the top wall of the casing 1.

11 are stuffing boxes secured in orifices 59 formed in the top wall 2 adjacent to the side walls 3 and in proximity to the front and back walls 4 and 5. 12 are brackets located at each side of the casing and secured to the top wall 2 centrally thereof 60 between the stuffing boxes 11. 13 are pivots carried by the brackets 12. 14 is a port ring which is mounted upon the annular member 8 so as to be turnable thereon. The port ring 14 is provided with port openings 65 16 which may be carried circumferentially in and out of alignment with the port openings 9. 15 are lugs extending from the port rings at diametrically opposite points. 17 and 18 are control rods slidable vertically 70 within the stuffing boxes 11 and connected at their lower ends to the lugs 15 of the port rings 14 located at each side of the casing 1. The control rods 18 are connected to the lugs 15 by pins or bolts 19. 20 are forked 75 upper ends to the control rods 17 and 18. 21 is the controlling lever, which is bifurcated as at 22, the arms 23 of which are pivoted upon the journal pivots 13 are provided with longitudinal slots through which pins carried by the forked upper ends 20 of the control rods extend.

It will be understood that the pivot 13 is located equidistant between each pair of control rods 17 and 18. 24 is a cylindrical member extending across the casing and fitting at its ends within the annular members 8. The ends of the cylindrical member 24 bear against the side wall of the casing 80 around the openings 7 and thereby serve to reinforce such side walls and also to protect the driving shaft hereinafter described.

25 are bearing members located at each side of the casing 1 at a suitable distance therefrom in which is journaled a driving 95 shaft 26 which extends centrally through the opening 7 and through the cylindrical member 24. 27 are right and left hand water wheels mounted upon the shaft 26 at each side of the casing and provided 100 with elongated buckets 29 attached around 105

the outer periphery of the body 28 of the wheel and are substantially semi-cylindrical in section. The buckets or blades 29 are set at an angle preferably at 5 forty-five degrees and have their inner ends bevelled so as to fit against the face of the casing 1. The angle at which the vanes are set of course will depend upon the varying head and water conditions encountered. 10 10 indicates a pair of tail race covers which are indicated by dotted lines in Fig. 1 and serve to divert the spent water from the machine into the tail race.

Having described the principal parts involved in my invention I will now briefly describe the operation of the same.

The water supply from which power is to be derived is fed to my device in the usual manner entering the casing through the supply pipe 10 which as will be readily seen is at right angles to the direction of flow through the water wheels 27. The water passing into the casing flows in opposite directions to the port openings 16 and 9 at each side of the casing and impinges upon the blades of the water wheels 27 so as to revolve the same and drive the shaft 26.

In order to control the flow of water through the port openings the lever 21 is 30 raised or lowered thereby turning the port rings 14 to regulate the size of the opening formed by the relative position of the port openings 16 to the openings 9.

It will thus be seen that the water flow 35 producing the motive power is at right angles to the inflow and therefore any stones or other foreign matter carried into the casing by the incoming water will drop to the bottom of the casing and will therefore not 40 pass to the port openings and clog the same or tend to break the buckets of the water wheels. The discharge of water from the vanes is effected on the opposite side of the impact thereon so that the tendency of water roping around the periphery of the vanes is overcome. The spent water passes downward through suitable tailing covers and tail races.

What I claim as my invention is:

50 1. A water wheel device comprising a main shaft, a casing through which the main shaft extends having port openings in the opposing walls arranged concentrically to the main shaft, port rings turnably mounted within the casing having port openings adapted to be carried in and out of a registering position with the port openings of the casing, manual means for simultaneously adjusting the port rings at each side of the casing, and water wheels mounted upon the main shaft exteriorly of the casing at each side thereof and provided with buckets set in right and left angular positions on the periphery against which the water is adapted to be directed from the port openings at

each side of the casing transversely in the corresponding wheel.

2. A water wheel device comprising a main shaft, a casing adapted to receive the water flow and through which the main shaft extends and having port openings in a wall thereof arranged concentrically with the main shaft, a water wheel mounted upon the main shaft on the outside of the casing and having angularly set buckets secured to its periphery against which the water from the port openings is directed in a transverse direction, a port ring turnably mounted within the casing so that its port openings may be carried into and out of a registering position with the port openings of the casing, and manual means located exteriorly of the casing for regulating the position of the port rings in relation to the port openings of the casing.

3. A water wheel device comprising a main shaft, a casing adapted to receive the water flow and through which the main shaft extends and provided with port openings in opposing walls thereof arranged concentrically of the main shaft, an annular ring secured to the casing at each side thereof, a cylindrical member fitting at its ends within the opposing rings, a port ring turnably mounted upon each of the aforesaid rings and having port openings coacting with the port openings of the casing, water wheels mounted upon the shaft exteriorly of the casing and provided with right and left angularly set buckets against which the water from the port openings is discharged transversely, and manual means for controlling the position of the port rings from the exterior of the casing.

4. A water wheel device comprising a main shaft, a casing through which the main shaft extends having port openings arranged concentrically in the opposing walls thereof, bucket wheels adapted to receive the water flow from the port openings, a port ring turnably mounted at each side of the casing and having port openings coacting with the port openings of the casing, vertically movable rods guided vertically within a wall of the casing and pivotally connected at their lower ends to the port rings at diametrically opposite points, a lever pivotally mounted upon the casing over the centre of the port rings and with which the control rods engage at each side of the main shaft.

5. A water wheel structure comprising a casing having openings formed in opposite wall portions thereof and a series of outlet ports spaced around each of said openings, a hollow sleeve extending between and connecting said opening, a ported disk rotatably mounted at each end of said sleeve for covering and uncovering the adjacent series of ports, a single lever connected to both of

said disks to actuate the same, a shaft extending through said cylindrical sleeve, bearings supporting said shaft and a pair of water wheel fixed to the shaft, each of 5 said water wheels being disposed in proximity to the ports formed in the adjacent wall of the casing.

Dated at Vancouver, B. C., this 17 day of July, 1922.
